Primary Examiner — Keli L Hill*Assistant Examiner* — Harold E Blackwell, II(74) *Attorney, Agent, or Firm* — Nitin Kaushik(57) **CLAIM**

The ornamental design for a mushroom solarstake light, as shown and described.

DESCRIPTION

FIG. 1 is a front perspective view of a mushroom solarstake light, showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view of thereof, provided for clarity of illustration; and,

FIG. 7 is an enlarged bottom plan view, provided for clarity of illustration.

The broken lines in the drawings illustrate the portions of the mushroom solarstake light, which form no part of the claimed design.
